UNITED STATES PATENT OFFICE.

A. A. HANSCOM, OF SACO, MAINE.

INK-ROLLER.

Specification of Letters Patent No. 20,710, dated June 29, 1858.

To all whom it may concern:

Be it known that I, ALPHEUS A. HANS-
5 com, of Saco, in the county of Yorke and
State of Maine, have invented certain new and
useful Improvements in Hand Inking-Rollers;
and I do hereby declare that the following
is a full, clear, and exact description
of the same, reference being had to the ac-
companying drawing and to the letters of
10 reference marked thereon.

The nature of my invention consists in
suspending and adjusting the inking roller
in a rolling frame in the manner that will
be hereinafter described.

15 That those skilled in the arts may use and
manufacture my invention I will proceed to
describe its construction and operation.

In the annexed drawings, Figure 1
20 is a side elevation, Fig. 2 is an end view,
Fig. 3 a top view of the cross frame of the
carriage.

B, is the inking roller. C represents a
carriage in which this roller is suspended
25 the triangular pieces (d d) being a portion
of said carriage in which are secured
the small wheels (e e) on which the
carriage rolls. Screws are secured to the
upper portion of these triangular pieces
30 (d d) which pass through the connecting
crosspiece as seen in Fig. 1 and are made
fast by means of nuts (o). These pieces
may be made adjustable, the screw of one
working in the slot (i) for the purpose of
35 bringing the wheels nearer together so that
the carriage may be adjusted to suit different
sized frames for forms.

(m m) are rods, which are provided with
screws (a a) at their upper extremity pro-
40 vided with holes at their lower extremity,
into which pass the small shafts in the ends
of the roller B.

(S) is a piece of metal of the peculiar
form herein shown of which, s' s', are parts,
45 and through which the rod (m) passes.

(n) is a plate provided with a screw, which
screw passes through the crosspiece C, the
carriage and metal piece (S), and by means
50 of nut (u) secures said piece, S, to the car-
riage. The screw of plate (n) works in the
slots, h h, thus allowing the roller to be ad-
justed longitudinally.

(c c) are nuts which pass over the screws
(a a) and by means of which the roller is
55 adjusted vertically.

In the operation of this roller it will be

seen that the wheels (e e) roll upon the
frame in which the form is placed and these
wheels may be brought closer together to
suit the size of the frame. The inking
50 roller being provided with ink is lowered
by means of nuts (c c) on to the type. The
operator then by taking hold of the handles
(g g) may roll the carriage backward and
forward over the type until sufficiently
55 inked.

The advantages of this arrangement are
many: among them the following will
readily occur to a practical printer:

1. The roll moves more easily over the
form: because the force which propels it is
not constantly pressing it more heavily upon
the type, and because it touches nothing
but the type, and does not fall into open
70 spaces in the form, such as occur between the
pages in a book form.

2. It prevents the too hard pressing of the
types into the ink roll (when soft) and con-
sequent inking of their sides below the face,
which inking tends to make a foul impres-
80 sion, and has always been a perplexity to the
printer, especially in working open forms,
such as blanks. By applying the ink solely
to the face of the type, this roller enables
the pressman to obtain a clean impression
85 upon the paper.

3. It prevents the cutting of the com-
position of the roll when used on open or rule
work enabling the printer to work the most
difficult forms of this sort as easily as com-
mon forms, and with as little injury to the
90 roll.

4. The roll will keep clean much longer;
for it cannot fall upon the furniture (wood
&c. by which the types are locked up) and
gather upon its surface the dust or dirt
95 thereon.

5. It saves ink; because it applies ink only
to the face of the types, where it is wanted
which is not generally the case with the
common roller.

6. It prevents the smutting of the margins
of the paper when no frisket is used; be-
cause not inking the furniture, there is no
ink thereon to smut the margins.

7. It admits of the same graduation of
the pressure of the ink roll upon the ink
table which it does upon the types, and may
thus facilitate the distributing of the ink
upon the roll, and prevent tearing the com-
position of the roll when soft and sticky.

Having thus fully described my invention what I claim is—

1. The employment of the several parts specified for the purpose of adapting the carriage to different sized forms, as set forth.

2. Suspending the inking roller (B) in the rolling carriage (C) constructed in the manner herein set forth; and regulating, and stationing said roller by means of

screws (*a a*) and nuts (*c c*) for the purpose of making an adjustable hand roller for inking type, the peculiarities and advantages of which, are herein fully described.

ALPHEUS A. HANSCOM.
